UNITED STATES PATENT OFFICE.

GEORGE E. VAN GUYSLING, OF BOSTON, AND JOHN G. W. ROMANS, OF WEYMOUTH, MASSACHUSETTS.

DESIGN FOR A CASE FOR COIN-OPERATED WEIGHING-MACHINES.

SPECIFICATION forming part of Design No. 36,182, dated December 30, 1902.

Application filed September 19, 1902. Serial No. 124,118. Term of patent 14 years.

To all whom it may concern:

Be it known that we, GEORGE E. VAN GUYSLING, residing at Boston, Suffolk county, and JOHN G. W. ROMANS, residing at Weymouth, Norfolk county, Massachusetts, citizens of the United States, have invented and produced a new, original, and ornamental design for a Case for Coin-Operated Weighing-Machines, of which the following is a specification, reference being had to the accompanying drawings, forming part thereof.

In the drawings, Figure 1 is a view in side elevation, showing a weighing-machine case shaped and ornamented in accordance with our design. Fig. 2 is a view in front elevation thereof. Fig. 3 is a cross-sectional view of the column, taken on the line S³S³. Fig. 4 is a similar view taken on the line S⁴S⁴. Fig. 5 is a view in rear elevation of the case, and Fig. 6 is a view in elevation of the side opposite that shown in Fig. 1.

As shown in the drawings, the leading or material features of our design are as follows: Viewed from the front, as in Fig. 2, the tapering column 1 is of oval or elliptical outline in cross-section, as shown in Figs. 3 and 4, the door 2 appearing as a vertical panel in the front wall of the column about midway of its length and ornamented by a suitable edging and central figure, the floral scrolls 3 above and below the panel, the

head 4 surmounting the column and containing a circular dial 5, surrounded by an ornamental ring 6, and the portion 7 of the case tapering from the head toward the column 35 and ornamented with scrolls. Viewed from the rear, as in Fig. 5, the intertwined vines 8 extend from the base to the head of the column and are caught at points by bows of ribbons, the face in profile with proper head-dress appearing within an ornamental ring-molding of the circular head, the tapering portion of the case uniting the head and column and the scroll ornamentation thereon. As viewed from the right-hand side, as in Fig. 45 6, the door 10 appears as a panel in the side wall of the head and is ornamented with an edging and central figure.

Having described our invention, what we claim as new, and desire to protect by Letters 50 Patent, is—

The ornamental design for a case for coin-operated weighing-machines, as herein shown and described.

In testimony whereof we have signed our 55 names to this specification in the presence of two subscribing witnesses.

GEORGE E. VAN GUYSLING.
JOHN G. W. ROMANS.
